UNITED STATES PATENT OFFICE

2,265,606

HOLDER FOR THE PAPER OF A PAPER
BREAKER GUN

Otto A. Langos, Chicago, Ill., assignor to Alfred F. Langos, Otto E. Langos, Harold L. Langos and Matilda R. Langos, partners, doing business as Langson Manufacturing Company, Chicago, Ill.

Application February 2, 1937, Serial No. 123,661

5 Claims. (Cl. 242—55.2)

This invention relates to toy air guns producing the sound of a gun shot by bursting paper with compressed air, and more in particular to a guide and support for a roll of paper in combination with the gun disclosed in my prior application Serial No. 72,707, filed April 4, 1936, now Patent No. 2,083,535 and as an improvement on such combination structure is a continuation in part of said application.

Although the paper holding structure illustrated and described in my earlier filed application proved satisfactory in a measure, it was found that in some instances the paper roll would get out of its normal position and interfere with the desired feeding operation of the paper in the gun. Furthermore, the former retaining device afforded little protection to the roll of paper in keeping it from snarling, and particularly in preventing it from being torn with rough handling.

It is an object of the present invention to provide, in a pleasingly appearing and efficiently operating combination, a paper breaker toy gun and an improved holder for supporting rolled paper to feed through the gun.

One of the features of the present invention is the provision of a simplified firing material support in combination with an air gun acting upon such firing material.

Another object is to provide a paper holder for such a gun, which holder will retain a paper roll against unrolling to an undesirable amount or becoming loosened and falling to one side or the other out of the normal rolled position at right angles to the rotating axis of the roll, during all kinds of handling of the gun.

A further object of the invention is to provide a simplified paper holder wherein a portion thereof cooperates in the assembly of the compression chamber of the toy gun and in forming an outlet from said chamber at one end thereof.

A still further object is to provide a holder for rolled paper, for a feeding movement in a continuous strip, said holder including a housing conforming substantially to the shape of the paper roll, and having retaining means rotatably mounted thereon for retaining the roll therein.

Other objects and advantages of the invention will be apparent from the following description, taken with the drawing, in which:

Fig. 1 is a side elevation of the complete gun and paper holder assembly in its preferred embodiment.

Fig. 2 is a fragmentary front elevation of the structure of Fig. 1.

Fig. 3 is a sectional view along the line 3—3 of

Fig. 2, and with the gun pointing in the opposite direction of that illustrated in Fig. 1.

Fig. 4 is a fragmentary side elevation of the complete paper holder of Fig. 3.

5 Fig. 5 is a fragmentary top plan view of a modified embodiment of the paper holder in combination with the gun of Fig. 1.

Fig. 6 is a sectional view along the line 6—6 of Fig. 5.

10 In practicing the invention, a paper bursting toy gun is provided, having a compression chamber in the barrel thereof, and means for sealing a paper strip across an outlet from the compression chamber to burst the paper with compressed air. The paper is fed in a continuous strip from a roll carried in a two-piece housing above the gun barrel, with a portion of the housing extending downwardly and cooperating to form the outlet at the end of the compression chamber of

15 20 the gun. The housing is provided in a substantially cylindrical casing to correspond with the form of the paper roll, and has a paper insertion opening in the face of the casing, and paper retaining means rotatably supported thereon.

25 30 To facilitate reference to my prior application on that structure which is common to that application and to the present application, the same reference characters primed are applied to such common structure.

35 Fig. 1 illustrates the toy gun of my prior application referred to above, having a handle 11' and trigger member 63' to be grasped by the user with the trigger operating through the spring and release mechanism described in said application, and including a piston 28' (Fig. 6) and compression spring 34' carried thereon. A two-piece gun barrel 12' carries a cylinder 16' in the front end thereof to in turn enclose the piston and spring mechanism having a leather washer 32' on

40 45 the end of the piston to engage the inside wall of this cylinder and compress the air therein as the piston is moved forwardly under spring pressure after release thereof at the end of the cocking action by the trigger member 63'.

45 50 As has been explained in the above noted prior application, and as will be apparent from Fig. 6 which illustrates the gun structure for both embodiments of the present invention, a strip of paper 47' is sealed across the outlet from the cylinder 16' to be burst by the discharge of air from said cylinder. The strip of paper 47' is fed from a roll of paper 51' by paper sealing and feeding mechanism including a metal slide 45' with a front end or sealing portion 48' and a

55 55 movably carried feeding jaw 56' on the bottom

of the slide having teeth 51' engaging the paper 47' and extending to a feeding plate 39' integral with the mounting or plate portion 37' for the roll carrying housing 76, as will be hereinafter described. The plate 39' extends upwardly over the mounting portion 37' having an aperture therein and an upset flange 30' which is pressed over the flanged end 36' of the cylinder 16' to rigidly mount the housing 76 on the cylinder and barrel assembly of the gun. A cupped ring 42' is inverted at the end of the cylinder to cooperate with the flanges 30' and 36' to form a buffer against which the fixed washer on the piston may press and cooperate with the flange 30', especially, to retain a rubber grommet 41' in place, to provide a cushion against which the sealing portion 48' presses the paper 47' to provide an air tight seal and make possible the bursting of the paper with a loud noise.

The air gun is a repeating device, and will fire or burst the paper as rapidly as the operator may compress the trigger member 63' with his fingers to cock the gun and permit the release of the piston.

The preferred embodiment of the combination is illustrated in Figs. 1 to 4 inclusive, and shows the housing 76 supported above the gun for carrying the roll of paper 51'. The housing includes a semi-cylindrical casing 77 (Figs. 3 and 4), and integral side walls 78 and 79 bent to right angles with the casing 77 and connected thereto at short connecting portions, as indicated at 80 in Fig. 3. The casing 77 with its integral side walls 78 and 79 extends through the downwardly extending mounting plate portion 37' so that all of these portions are stamped out from a single piece of metal.

As previously described, the mounting portion 37' is provided with a flanged aperture for securing the mounting portion, and in fact the entire housing 76 itself, to the cylinder 16' in the gun proper. The casing 77 extends from the bend 81a to a curved integral lip 82 which is formed so as to engage the transverse or handle portion 83 of the roll retaining member 84 in a substantially spring catch action.

A retaining member 84 is formed from wire substantially of the size indicated in Fig. 1, and includes a transverse axis portion 85 and a radial arm portion 86 extending to the handle portion 83. The radial arm portion 86 is of a length slightly greater than the radius of the circular wall 79. The member 84 is rotatably mounted in correspondingly positioned apertures 87 and 88 in the side walls 78 and 79 respectively of the housing. In the original mounting of this member, the normal sized outer end of the portion 85 is inserted through aperture 88 and then flattened out in any desired manner to the configuration at 89 shown particularly in Fig. 2. This flattened end 89 may be inserted through the elongated slot 87, yet will not pass through the corresponding aperture 88 in the opposite side wall of the housing. To insert the paper roll 51' in the housing, the handle portion 83 is snapped out of the lip 82 and brought forwardly until the flattened end 89 may be withdrawn through the slot 87, after which the paper roll 51' is inserted in the walled housing, and the retaining member 84 reinserted through the slot 87 and moved to the position shown in Figs. 1 to 4. In the commercial embodiment of this structure it has been found that the paper roll is amply protected against damage, feeds satisfactorily out of the housing, and is retained by

the walls 78 and 79 from falling to one side or the other.

A further embodiment of the combination structure is illustrated in Figs. 5 and 6, and includes a housing 90 having a casing 71a which extends downwardly through the mounting portion 37' as described with respect to the embodiment of Figs. 1 to 4, and extends upwardly in cylindrical form to an upper edge slightly higher than the top of the casing 77 of Fig. 3 for instance. A slidable cover 91 is rotatably secured at apertures 92 in the side walls 93 similar to the side walls 78 and 79 and integral with the casing through a connecting portion at 80, identical with this portion illustrated in Fig. 3. The cover is shown in full lines in closed position (Fig. 6) to retain the roll of paper 51' therein, while the dotted lines in Fig. 6 indicate the cover in open position. A projection 94 in the casing 77a serves to releasably lock the cover in closed position, while the opening of the cover is facilitated by a bevelled portion 95 which helps to guide depression 96 over the projection 94 to readily open the cover. A guideway 97 centrally of the cover and guideways 98 adjacent the edges fit over the projection 94 and beads 99 respectively as the cover is moved to an open position.

When the cover is in closed position, a slot formed by the lower edge 100 of the cover and 30 the bend 81a in the casing 71a forms a guiding 35 opening to guide the paper from roll 51' into the feeding mechanism of the gun.

In utilizing only a two-piece assembly for the complete housing for the paper roll, and then employing the mounting portion of that housing to cooperate with the barrel and cylinder structure of the gun to complete the assembly and provide an outlet for the cylinder, a minimum amount of material is necessary in the structure, and yet ruggedness, simplicity and a certain amount of artistic merit are provided in the paper holder.

Although the invention has been described in its preferred embodiments, it is understood that it is not limited thereby, but is limited only by the scope of the appended claims.

I claim:

1. A housing for a roll of strip material including a substantially semi-cylindrical casing and integral side walls, and a movable retaining member for said roll supported in said walls having an axial portion extending through the center of said roll, and a handle portion releasably locked on said casing.

2. A holder adapted to be supported on a toy gun for carrying a paper roll including a casing wall having releasable locking means at the top thereof, side walls integral with said casing wall and at right angles thereto, a roll retaining member rotatably carried in said side walls by an axis portion formed against removal from one side wall and having a radial portion on the outside of said one side wall extending to a combination handle and locking arm for releasable locking on said casing wall.

3. A housing forming a cage for the reception of a roll of paper, having an opening for the insertion of such a roll, and having pin insertion openings in its side for the insertion of a pin through the center of the roll, a pin for insertion in said openings and retaining the roll of paper, and a roll of paper having an internal diameter sufficiently large to provide considerable tolerance in the positioning of the roll to secure alignment of the passage therethrough with the pin

insertion openings in the housing and having an external diameter so related to the internal shape of the housing as to align said passage with said pin insertion openings whereby the pin may be inserted when a new roll has simply been dropped into the cage.

4. A housing for a roll of strip material and a rotatably movable retaining member having an axial portion extending through the housing at a central position thereof to retain said roll rotatable in said housing, and having a handle portion extending generally radially from the axial portion and adapted to engage the housing to prevent accidental rotation of the handle portion, said housing having a slot through which the axial portion passes, and said axial portion having a laterally extended formation thereon adapted to pass through said slot when the han-

5 dle portion is in one position to permit removal of the strip material but being engaged by the walls of the slot to prevent axial movement of the retaining member when the handle is locked in another position.

5. A paper support for mounting on a paper burster toy, including a mounting portion, a pair of apertured sidewalls extending from said mounting and both being rigid with reference thereto, a pivoted member having an axis portion pivotally supported at the apertures in said sidewalls, and having a handle portion parallel to said axis portion and extending on the outside of at least one of said sidewalls at right angles thereto, and said paper support having a portion thereon for releasably retaining said handle portion in paper holding position.

OTTO A. LANGOS.
